Specification of Letters Patent.

Patented May 6, 1919.

Application filed January 8, 1918. Serial No. 210,864.

To all whom it may concern:

Be it known that we, GEORGE HARVEY KNIGHT, of 5 Great Winchester street, London, England, and HERBERT GEORGE THACKRAY, 24 Eden Place, Stanwix, Carlisle, Cumberland, England, have invented certain new and useful Improvements in or Relating to Labels and Capsules, of which the following is a specification.

10 This invention relates to labels and capsules. The object of this invention is to provide a label adapted to be placed over the cork and neck of a bottle, jar or vessel.

A label or capsule made in accordance 15 with this invention is formed of paper, linen, cotton or like material, with or without a metallic surface, and comprises a part adapted to be wrapped around the neck of the bottle which may be termed the neck part, 20 side or skirt, and a part applied to the top of the bottle to cover the cork or stopper, provided with tongues arranged on the periphery thereof adapted to be folded downward, which may be termed the top or cork 25 part, the whole forming an inverted cup-shaped capsule when in position. We have found that seven tongues may be advantageously employed in forming a cup-shaped capsule in accordance with this invention, 30 but the invention is not limited to this number.

Referring to the drawings filed herewith:

Figure 1 is a plan of a label adapted to fit a bottle having a neck which is smaller 35 near the top than lower down.

Fig. 2 is a plan of a label adapted to fit a bottle having a neck which is larger near the top than lower down.

Fig. 3 is a plan of a label adapted to fit 40 a bottle with a cylindrical neck.

Fig. 4 is a plan of a label adapted to fit a bottle having a neck partly cylindrical.

Fig. 5 is a plan of a modified form of 45 label adapted to fit a bottle having a neck which is smaller near the top than lower down.

a is the skirt part, *b* the top or cork part, provided with tongues *c*.

In each of the forms shown, the skirt part 50 is integral with the top part and the tongues are disposed on a part of the periphery of the top part; one edge of the skirt part being practically tangential to the circle about which the tongues are arranged, so that when

the tongues are turned down and the skirt 55 part wrapped on top of the tongues a cup shaped capsule is formed on the bottle, and causing no more plaiting or folding of the material than with metal capsules which this is intended to supersede.

In the form shown in Figs. 1 and 2, the skirt parts are formed with two curved edges and two radial edges.

In the form shown in Fig. 3 the skirt part 65 is rectangular.

In the form shown in Fig. 4 the skirt part is slit along a line *d d*.

In the form shown in Fig. 5 the top or cork part is disposed one side of the skirt part, whereas in Figs. 1 to 4 the top part is 70 disposed centrally of the skirt part.

The labels are or may be gummed on one side and printed on the other side. The label or capsule being in one piece can be applied to and fixed to the bottle with great 75 rapidity.

In practice we prefer to use paper or other material on which can be printed color and matter as may be desired.

The method of application to a bottle is 80 as follows:

These labels are damped on their gummed side or otherwise rendered tacky and the skirt part applied to the neck of the bottle. The top part is then folded down over the 85 cork or stopper and the tongues bent downward over the edge of the neck of the bottle. The skirt part is then brought around the neck, inclosing and binding the tongues, the two extreme ends being joined and completing the cup.

Preferably the labeled bottle is placed in a capsuling machine such as is usually used for closing metal capsules on to bottles, so as to better complete the operation.

Labels adapted to form capsules in accordance with this invention can be packed or stocked so as to occupy much less space than metallic or plaited paper capsules hitherto employed.

Labels may be made in various forms and shapes with or without slits to fit bottles and jars of various shapes.

When the labels are treated with varnish on the surface they protect the label and cork from damp and render them easily cleansed and have the appearance of a metallic capsule.

When made from a paper having a metallic surface and either with or without a transparent printed color, capsules can be produced to meet the requirements in color and appearance customary in certain trades not obtained from paper with an opaque and varnished surface.

The invention provides a suitable and adequate capsule to prevent peculation or substitution of contents of bottle, jar, or vessel, in the same way but to a greater extent than metal capsules previously in general use, with the advantage that these paper capsules can be produced at a much lower price.

15 A label or capsule made in accordance with this invention cannot be removed and replaced without detection. They can be printed in any colors required and have the advantage of giving brighter and cleaner 20 colors than could hitherto be produced on metal and overcome the difficulty of producing printed matter on the skirt of plaited paper capsules.

What we claim and desire to secure by 25 Letters Patent is:

1. A bottle capsule consisting of a neck-engaging portion, a top-engaging portion integrally connected to the neck-engaging portion, and a series of integral tongues extending radially from the edge of the top-engaging portion and adapted to be bent downwardly against the side of a bottle neck and to be confined by the neck-engaging portion, the top-engaging portion being 30 so related to the neck-engaging portion that the inner longitudinal edge of the latter extends tangentially to a circle passing through the edge of the top-engaging portion and through the base portions of said 35 tongues.

2. A bottle capsule consisting of a neck-engaging portion, a top-engaging portion integrally connected to the neck-engaging

portion, and a series of integral tongues extending radially from the edge of the top- 45 engaging portion and adapted to be bent downwardly against the side of a bottle neck and to be confined by the neck-engaging portion, the top-engaging portion being so related to the neck-engaging portion that 50 the inner longitudinal edge of the latter extends tangentially to a circle passing through the edge of the top-engaging portion and the base portions of said tongues, and the tongues adjacent to the neck-engaging portion extend in a direction generally parallel to the adjacent edge of the neck-engaging portion.

3. A bottle capsule consisting of a neck-engaging portion, a top-engaging portion 60 integrally connected to the neck-engaging portion, and a series of integral tongues extending radially from the edge of the top-engaging portion and adapted to be bent downwardly against the side of a bottle 65 neck and to be confined by the neck-engaging portion, the neck-engaging portion having longitudinal edges which are curved and parallel to each other, the top-engaging portion being so related to the neck-engaging 70 portion that the inner curved edge of the latter extends tangentially to a circle passing through the edge of the top-engaging portion and the base portions of said tongues, the tongues adjacent to said neck- 75 engaging portion extending in a direction generally parallel to the adjacent edge of the neck-engaging portion.

In witness whereof we have signed our names to this specification.

GEOERGE HARVEY KNIGHT.

HERBERT GEORGE THACKRAY.
